UNITED STATES PATENT OFFICE

JACOB C. STEDMAN, OF MEMPHIS, TENNESSEE

DESIGN FOR A HOUSE

Application filed February 4, 1933. Serial No. 47,109. Term of patent 14 years.

To all whom it may concern:

Be it known that I, JACOB C. STEDMAN, a citizen of the United States residing at Memphis, Shelby County, State of Tennessee, have invented a new, original, and ornamental Design for a House, of which the following is a specification, reference being had to the accompanying drawings, forming part thereof.

Figure 3 is an elevational view of the other end of the house showing my new design.

I claim:

The ornamental design for a house as shown.

JACOB C. STEDMAN.
